UNITED STATES PATENT OFFICE

2,429,846

ELECTRIC CIRCUIT INTERRUPTER

Joseph W. Seaman, Kennett Square, Pa., assignor
to General Electric Company, a corporation of
New York

Application March 24, 1944, Serial No. 527,913

7 Claims. (Cl. 200—144)

1

My invention relates to electric circuit interrupters, and more particularly to air circuit interrupters of the type wherein the arc is to be interrupted within confining or partially confining means, such as an arc chute.

Heretofore electric circuit interrupters of the above mentioned type have comprised a plurality of relatively movable contacts arranged adjacent to an arc chute with means such as magnetic blowout coils, air jets or the like, for forcing the arc into the arc chute where it can be interrupted. In some of these prior art constructions where the arc is drawn outside of the arc chute and means are provided to force it into the arc chute, a current level is sometimes reached with the arc core having such a large diameter that the magnetic blowout means, for example, cannot force the arc into the part of the chute where the interruption takes place with the result that failure occurs.

It is an object of my invention to provide an improved electric circuit breaker in which it is impossible to have a failure to interrupt the circuit due to failure to move the arc into the interrupting part of the arc extinguishing structure.

It is another object of my invention to provide a new and improved electric circuit interrupter in which the arc is drawn in the part of the arc extinguishing structure where interruption finally occurs.

It is another object of my invention to provide an electric circuit interrupter including a plurality of parallel arranged contacts separable within narrow slots of an insulating, arc extinguishing structure.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a front view, partly in section, of an electric circuit breaker embodying my invention; Fig. 2 is an exploded view in perspective of the arc extinguishing structure for one pole of the electric circuit interrupter, shown in Fig. 1; Fig. 3 is an enlarged sectional view taken on line 3—3 of Fig. 1, and Fig. 4 is a sectional view taken on line 4—4 of Fig. 3.

It has been discovered that an arc can very effectively be interrupted when confined within a narrow slot contained in an insulating arc extinguishing structure. If the contacts of an

2

electric circuit interrupter were separated so as to draw the arc directly within such a narrow slot the interruption could take place there and no means would be required as in prior art devices to force the arc to the point in the arc extinguishing structure where interruption can take place, the arc being drawn at a different point. Due to the high currents which must be carried by the contacts of electric circuit interrupters, the contact area from the standpoint of successfully withstanding the burning action of the arc, must be quite large so that such contacts would be too large to operate within the narrow slots which I have discovered are particularly well adapted to effectively interrupt an arc drawn within such slots. My invention is concerned with an arrangement in which one or more relatively narrow contacts connected in multiple are provided so that each contact can move within the narrow slot most effective for arc interruption, and the number of such multiple arranged contacts being dependent upon the magnitude of the current to be carried and interrupted.

Referring now to the drawing, I have illustrated an electric circuit interrupter generally indicated at 10, which might be a single-pole or multiple-pole circuit interrupter. In Fig. 1 a three-pole circuit interrupter is indicated comprising an insulating casing 11 with three upper terminals 12, and three lower terminals 13 mounted on the casing. Although each pole of the circuit interrupter 10 may include one, two, or more contacts in multiple, I have specifically illustrated an arrangement in which two contacts 30 are provided in multiple. These contacts are not visible in Fig. 1 but the supporting rods 14 for the movable contacts are clearly visible in Fig. 1 as well as in Figs. 3 and 4. With the slots of the arc chute designed for optimum current interruption as will be described hereinafter, I have found that two contacts in parallel are satisfactory for a 100-ampere breaker, while three contacts in parallel might be desirable for a 200-ampere breaker, and four contacts in parallel might be 40 desirable for a 600-ampere breaker, it being understood that each pole of the circuit breaker is provided with such multiple contacts.

The operating mechanism and other features of the circuit breaker disclosed in Fig. 1 are not 50 my invention but are disclosed and claimed in the copending application of John A. Favre, Serial No. 555,630, filed September 25, 1944, and assigned to the same assignee as the present application.

Mounted in the upper part of casing 11 of circuit interrupter 10 are a plurality of arc extin-

guishing structures or arc chutes 15, one for each pole of the circuit interrupter. Each of these arc chutes, best shown in Figs. 2, 3, and 4, preferably comprises a structure which may be removed as a unit if desired. Furthermore, these arc chutes are formed of an insulating material and preferably a bonded asbestos compound which might comprise a phosphoric asbestos compound which could be molded to the desired shape. The arc chute might also be made from asbestos board machined to the proper shape. Each arc chute or arc extinguishing structure comprises a pair of outer walls 16 and 17 which are adapted to be arranged in spaced parallel relationship. The arc extinguishing structure is divided into a plurality of narrow slots such as 18, by one or more insulating barriers 19. Since only two multiple contacts for each pole are illustrated, only a single insulating barrier 19 is required. Each of the members 16 and 17 is provided with an extension 20 at one edge thereof which cooperates with an extension 21 of insulating barrier or wall 19 to determine the spacing between the members 16, 17 and 19. The edge of barrier 19 opposite the edge upon which extension 21 is mounted is adapted to fit within a slot formed by cutaway portions of members 16 and 17. The arc chute is held together as a unitary structure by any suitable means, which is indicated in the drawing as by pins 22, one of which passes through the extensions 20 and 21 and the other of which passes through openings 23, 24 and 25 in members 16, 17 and 19, respectively.

Supported from the back wall of casing 11 in such a manner as to extend within the slots 18 of the arc chute 15 are stationary contacts 26 (Figs. 3 and 4) which are connected in parallel or multiple by flexible copper conductors 27 suitably connected to terminal 12. In order to prevent any magnetic forces produced by virtue of the current flowing through flexible conductors 27 from terminal 12 to the bottom of stationary contacts 26 from causing the arc to move downwardly on contacts 26 rather than upwardly, a magnetic shield 28 is provided which may comprise copper plated steel, or the like. This magnetic shield is mounted between flexible conductors 27 and contacts 26. A rivet 29 holds the shield 28 and flexible conductors 27 and the terminals 12 in proper alignment as a unitary assembly. This arrangement of the stationary contacts is not my invention but is disclosed in the above-mentioned Favre application.

Cooperating movable contacts 30 are adapted to be supported on movable conducting supporting rods 14 so as to move within the narrow slots 18 of the arc chutes 15. These rods are electrically and mechanically interconnected as indicated at 31 in Fig. 4. The movable contacts 30 are arranged so that the entire motion thereof is within narrow slots 18 so that the arc is always drawn at the place where it is to be interrupted and no means are required to force the arc into an arc chute, as was the case in prior art constructions. The open position of movable contacts 30 is indicated by dotted lines in Fig. 3. The movable contacts 30 are provided with a contact surface which is very narrow in the direction at right angles to the direction of contact motion as compared to the dimension of the contact surface in the other direction.

Upon separation of stationary contacts 26 and movable contacts 30 an arc will be drawn. Due to slight mechanical differences between the contacts, this arc will usually be drawn at one set

of contacts and means must be provided to immediately transfer this arc to all of the multiple contacts arranged in parallel since the ability for one slot to interrupt current is limited. To this end I provide the wall or barrier 19 between the slots 18 with a plurality of openings 32 to provide uniform distribution of the gases and consequently to produce parallel arcs, one in each slot with the current shared substantially equally between the arcs in the respective slots. Although the openings 32 have been indicated as circular openings, it should be understood that this is not essential and any other means for obtaining distribution of the arc gases between the slots 18 such as irregular shaped openings can of course be used.

The arc chute was designed by varying the size thereof, the slot spacing and the arrangement of the holes 32 for optimum current interruption. The greater the current to be carried by each contact in each slot, the wider the slot and the larger the openings between slots. I have found a slot with of less than one-half inch to be very desirable. An arc chute having a $\frac{1}{8}$ inch slot width with the openings 32 being $\frac{1}{16}$ inch in diameter spaced on $\frac{1}{2}$ inch centers with alternate rows of holes filling the intervening space appeared to yield the best results.

In order to cool the arc gases a suitable muffler 33 may be provided at the upper end of each arc chute. Such a muffler may comprise a series of U-shaped members arranged with the alternate U-shaped members inverted. This can be accomplished by supporting as by molding into member 16, for example, a plurality of inverted U-shaped members 33 of a length dependent upon the spacing between members 16 and 17. Similarly supported from the member 17, on the other hand, are the upright U-shaped members 34. Preferably these U-shaped members nest together so that the adjacent ends of two inverted U-shaped members 33 extend within one of the U-shaped members 34 and vice versa. In this manner a discontinuous sinusoidal metallic cooling member is provided against which the hot gases impinge. This muffler construction forms no part of my invention but is disclosed and claimed in the copending application filed concurrently herewith of Charles H. Titus, Serial No. 527,912, assigned to the same assignee as the present application, now Patent No. 2,408,352, issued September 24, 1946.

In view of the detailed description given above the operation of the circuit interrupter of my invention will be obvious to those skilled in the art. Upon separation of the contacts 26 and 30 within slots 18 (two parallel sets of contacts and two slots being shown, although three or more might be utilized), an arc is drawn between one set of contacts 26 and 30 within the associated slot 18. The arc gases formed are equalized immediately, and distributed between the slots, thereby equalizing the temperature gradient between the slots and hence permitting parallel arcs to be formed, one in each slot. Since the arc is drawn in the portion of the arc extinguishing structure where interruption is to occur, failure to interrupt by virtue of failure to move the arc into the arc chute is impossible. The narrow slot geometry of the arc chute causes immediate interruption of the arcs and the hot arc gases impinging against the members 33 and 34 of the muffler are rapidly cooled before leaving the arc chute.

While I have shown and described a particular

embodiment of my invention, it will be obvious to those skilled in the art that various changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States, is:

1. In an electric circuit interrupter comprising an arc extinguishing structure including a plurality of narrow slots displaced from each other by a wall of insulating material, a plurality of pairs of electrically parallel relatively movable cooperating contacts so mounted as to be respectively separable in said slots for drawing an arc within at least one of said slots, and means including openings in said wall for providing communication between said slots to tend to produce a uniform distribution of gases between said slots as well as to cause a plurality of parallel arcs to occur, one in each slot.

2. In an electric circuit interrupter comprising an arc extinguishing structure including an insulating member defining a plurality of narrow slots with a wall of insulating material between said slots, a stationary contact mounted in each slot, a plurality of cooperating movable contacts arranged one in each slot and movable therein so as to draw an arc in at least one of said slots upon separation of said stationary and movable contacts, said movable contacts being mechanically and electrically interconnected exteriorly of said arc chute, the number of said contacts and slots depending upon the current expected to be carried by said contacts, and a plurality of openings in said wall between said slots to tend to produce a uniform distribution of gases between said slots as well as to cause a plurality of parallel arcs to occur one in each slot.

3. An arc extinguishing device for a circuit interrupter comprising two spaced parallel-connected stationary contacts, two respectively cooperating spaced parallel-connected substantially simultaneously movable contacts, and insulating means forming two narrow slots having substantially the same width with an intervening wall of insulating material, said insulating means being adapted to be mounted on the circuit breaker with said contacts and the respectively associated cooperating movable contacts respectively positioned in said slots to strike an arc within at least one of said slots upon separation of the respectively cooperating contacts therein under predetermined current conditions in a circuit through the circuit breaker and to hold the extremities of said arc until extinction thereof.

4. An arc extinguishing device for a circuit interrupter having a plurality of spaced parallel-connected stationary contacts and a plurality of respectively cooperating spaced parallel-connected substantially simultaneously movable contacts, insulating means forming a plurality of narrow slots with an intervening perforated wall of insulating material between each of two adjacent slots, said insulating means being adapted to be mounted on the circuit breaker with one stationary contact and the respectively associated cooperating movable contact in each slot.

5. An arc extinguishing device for a circuit interrupter comprising two spaced parallel-con-

nected stationary contacts, two respectively cooperating spaced parallel-connected substantially simultaneously movable contacts, and insulating means forming two narrow slots with an intervening wall of insulating material, said insulating

means being adapted to be mounted on the circuit breaker with said contacts and the respectively associated cooperating movable contacts respectively positioned in said slots and said intervening wall being perforated for permitting a uniform distribution of gases between the slots and for causing a plurality of parallel arcs to occur one in each slot.

6. In an arc extinguishing device for a circuit interrupter having a plurality of spaced parallel-connected stationary contacts and a plurality of respectively cooperating spaced parallel-connected substantially simultaneously movable contacts, insulating means forming a plurality of narrow slots with an intervening wall of insulating material between each of two adjacent slots, said insulating means being adapted to be mounted on the circuit breaker with one stationary contact and the respectively associated cooperating movable contact in each slot and said walls being provided with a plurality of openings for permitting a uniform distribution of gases between the slots and for causing a plurality of parallel arcs to occur one in each slot.

15 7. In an arc extinguishing device for a circuit interrupter having a plurality of spaced parallel-connected stationary contacts and a plurality of respectively cooperating spaced parallel-connected substantially simultaneously movable contacts, insulating means forming a plurality of narrow slots of substantially the same width with an intervening perforated wall of insulating material between each of two adjacent slots, said insulating means being adapted to be mounted on the circuit breaker with one stationary contact and the respectively associated cooperating movable contact in each slot and said walls being provided with a plurality of openings for permitting a uniform distribution of gases between the slots and for causing a plurality of parallel arcs to occur one in each slot.

20 8. An arc extinguishing device for a circuit interrupter having a plurality of spaced parallel-connected stationary contacts and a plurality of respectively cooperating spaced parallel-connected substantially simultaneously movable contacts, insulating means forming a plurality of narrow slots of substantially the same width with an intervening perforated wall of insulating material between each of two adjacent slots, said insulating means being adapted to be mounted on the circuit breaker with one stationary contact and the respectively associated cooperating movable contact positioned in each slot to strike an arc within at least one of said slots upon separation of the respectively cooperating contacts 25 therein under predetermined current conditions in a circuit through the circuit breaker and to hold the extremities of said arc until extinction thereof.
